Specification of Letters Patent.

Patented Sept. 7, 1915.

Application filed May 2, 1913. Serial No. 765,145.

To all whom it may concern:

Be it known that I, CLIO B. Yaw, citizen of the United States, and resident of Arlington, in the county of Hudson and State of New Jersey, have invented certain new and useful Improvements in Type-Writing Machines, of which the following is a specification.

My present invention relates to tally strip mechanism for typewriting machines and its general object is to provide improved mechanism of the character specified.

To the above and other ends my invention consists in the features of construction, combinations of devices and arrangements of parts hereinafter described and particularly pointed out in the claims.

While applicable to typewriting machines generally, the preferred embodiment of my invention herein illustrated is applied to a No. 11 Remington front-strike typewriting machine. In the accompanying drawings, Figure 1 is a fragmentary end elevation, partly in section, showing the upper portion of a No. 11 Remington typewriting machine embodying my invention. Fig. 2 is a fragmentary front elevation partly in section of the same. Fig. 3 is a longitudinal sectional view of part of the tally strip line spacing devices. Figs. 4 and 5 are respectively left-hand and right-hand portions of a two-part or divided platen shown in central longitudinal section. Figs. 6 and 7 are detail views of platen connecting devices. Fig. 6 showing in plain some of the parts which appear in vertical section and in elevation in Fig. 5, while Fig. 7 is a perspective view. Figs. 8 and 9 are skeletonized end views showing the paper feeding and platen line spacing devices, the parts being differently related in the two views. Fig. 10 is a fragmentary view of some of the platen line spacing devices shown in Figs. 8 and 9 but in different relationships. Fig. 11 is a fragmentary plan view of the paper feeding devices coöperative directly with the platen.

Referring to Figs. 1 and 2 the main frame of the machine comprises posts 1 supporting a top plate 2 from which rise lugs 3 on which are supported grooved guide rails 4 that coöperate through anti-friction balls 5 with a front bar 6 and a

rear bar 7 of the carriage truck which further includes end bars 8 connecting said front and rear bars. Shiftably connected with said truck by devices 9 is a platen frame or carrier comprising end bars or plates 10 and cross rods or bars 11 and 12. The platen frame and its supporting truck 60 constitute a traveling platen carriage or carrier. The end bars 10 provide bearings for stub shafts 13 and 14 to the outer ends whereof are secured finger wheels 15 (Figs. 4 and 5). The shafts 13 and 14 assist to support a two-part or divided platen, the details whereof are illustrated in said Figs. 4 and 5. The left-hand platen section or element 16 of the platen is arranged coaxially with the right-hand or tally section 70 of said platen. These elements, sections or parts 16 and 17 may be considered as platens in themselves. The main platen 16 comprises a core 18 of wood and a sheath 19 of rubber. Secured to the left-hand end 75 of the platen 16 is a platen head 20 which receives screws 21 that screw into blocks 22 suitably secured to the interior of a tube or core 23 of metal that is driven into or otherwise secured in the bore of the wooden core 18. A dowel pin 24 connects the head 20 with the core 18. Said head fits over the shaft 13 and has an outwardly projecting hub which receives a screw 25 which abuts against the shaft 13 and secures it in 85 fixed relationship with the head 20 and platen 16. The shaft 13 bears in a flanged sleeve 26 that is screwed through an opening in the left-hand end bar 10 and is locked in place thereon by a check nut 27. A washer 90 28 is interposed between the sleeve 26 and the hub of the head 20 to assist in maintaining the platen 16 properly spaced from the end of the platen frame. The sleeve 23 extends rightward beyond the platen 16 and 95 is provided at its right-hand end with in-turned ears 29 which receive screws 30 by which the sleeve 23 and platen 16 are connected with clutch devices for releasably or disconnectably connecting the platen 16 with 100 its line spacing ratchet wheel 31. Said clutch devices are of the construction found in the No. 11 Remington typewriting machine and substantially disclosed in the patent to Woodward, No. 945,358, granted January 4, 1910, and include a clutch carrier

comprising a main hub 32 provided with slots 33 which receive clutch members 34 that engage with and clutch an inward rib 35 on the ratchet wheel 31 and are releasable to disengage said rib by rollers 36 which coöperate with the inner free ends of said clutch members 34. Said rollers are mounted in a frame 37 which is secured to the inner end of the shaft 14, which shaft is adapted to slide through the hub 32 and is pressed outward normally by a spring (not shown) contained in a barrel 38 secured to the hub 32. The rib 35 bears rotatably on the hub 32 and is undercut to bear on a plate 39 which is secured to said hub by the screws 30 that pass through the hub and are threaded into the ears 29. Preferably these ears are arranged in pairs spaced apart to receive suitably fixed blocks 40 which are threaded to receive the screws 30, the construction providing for ample stock into which said screws may be threaded.

It will be understood that normally the clutch members 34 hold the ratchet wheel 31 in fixed relationship with the sleeve 23 and the platen 16 so that line spacing movements communicated to the wheel 31 by the hand actuated line spacing devices herein-after described will be transmitted to the platen 16. When, however, the right-hand finger wheel 15 is pushed in it causes the rollers 36, acting on the clutch members 34, to disconnect the ratchet wheel 31 from the platen 16 so that the platen may be turned independently of its ratchet wheel. The ratchet wheel is held from displacement on the hub 32 by the plate 39 at one side and by a flange 32^a on said hub at the opposite side. A cover plate 32^b is preferably provided surrounding this flange when held in place by the end of the tube 23.

If desired, the clutch members may be locked in released position by devices comprising a flange 41 rigid on the shaft 14 and coöoperative with a detent 42 pivoted at 43 in a slot in a collar 44 that is secured by a screw 45 to a sleeve 46. Coöoperative with said detent is a spring 47. The sleeve 46 is bored out to provide a passage for the shaft 14 and is counterbored at its left end to receive the reduced or secondary hub portion 48 projecting rightward from the main hub 32. Said sleeve 46 is threaded into the right-hand end plate 10 of the platen frame 55 and is secured in place by a check nut 49. At its left end inside the end bar 10 said sleeve terminates in a flange 50.

The tally platen 17 is rotatably mounted on the tube 23 to the right of the platen 16 and comprises a tube or core 51 surrounded by a sheath 52 of rubber. The tube 51 has secured to its left end a shouldered platen head or annulus 53 which abuts against the platen 16 and bears rotatably on the tube 23. At its right end the tube 51 has secured to

it a platen head 54 which is provided with peripheral gear teeth as indicated at 55, thus becoming in effect a gear wheel which assists to connect the tally platen with its actuating devices and also with a take up 70 or receiving tally holder as hereinafter described.

The tally platen comprising the core 51, sheath 52 and heads 53 and 54 is adapted to turn freely on the tube 23, thus providing 75 for relative movements between the two platens or platen sections 16 and 17 and the platen 16 is also adapted to turn independently while the platen 17 remains motionless or quiescent. However, at times it may 80 be desirable to connect the two platens to turn as a single platen or device and to this end clutch or connecting devices are provided as illustrated in Figs. 4 to 7. Said clutch or connecting devices are under the 85 control of a push or pull button or finger piece 56 which is arranged or located outside the finger wheel 15, being mounted on a slide rod 57 which extends inward coaxially of the platen sections through an opening in the finger wheel 15 and the shaft 13, said shaft being bored out or made hollow for the purpose. At its inner end the rod 57 has suitably secured to it a coaxial cylindrical rod or device 58, the inner end of 90 which is rounded off to a point as indicated at 59, thus providing a cam. This pointed end or cam is adapted to coöperate with the end of the stem of a T-shaped operating 95 lever 60 that is arranged inside the tube 23 100 and is provided with a bearing stud 61 that bears in an opening in said tube. At the end opposite from the stud said lever projects through a slot 62 in the tube 23 and fits into the split or space 63 between the 105 ends of a split collar 64 which surrounds the tube 23 and is provided with a hole 65 which receives the portion of the stud 61 that projects outside the tube 23, thus providing a further bearing for said stud which 110 thus serves to connect the split collar 64 with the tube 23. Said collar is confined on the tube 23 between the platen head or flange 53 and a collar 66 which is secured 115 by a screw 67 to the tube 23 at the right of the split collar 64. Said collar 64 when disposed as in Fig. 6 bears loosely on the inner face of the tube or core 51 but when the button 56 is pushed in the cam 59 coöperates with the end of the stem of the lever 60, said end being pointed as indicated in Fig. 6, to cam said stem to one side. As a result the lever 60 is caused to turn on the stud 61, thus expanding the collar 64 and forcing it to frictionally engage with the tube 51 to frictionally connect the platen 17 with the platen 16. This style of friction clutch is substantially the same in principle as that disclosed in the patent to Carhart, No. 923,016, granted May 25, 1909. When 120 125 130

the button 56 is pushed in axially of the divided platen the stem of the lever 60 will ride up on the side of the inner end of the rod 58 and the friction of the parts will maintain said rod and the rod 57 and abutment 56 in a pushed-in position as long as desired, thus maintaining the clutch devices 64 and 60 in operation and the platens 17 and 16 connected so that line spacing movements communicated to the ratchet wheel 31 will be transmitted to both platens 16 and 17 as will also turning movements communicated to and by the finger wheels or platen knobs 15. When it is desired to disconnect the clutch devices the button 56 is pulled out until the parts are in the Fig. 4 position.

It will be noted that the normal position of the finger piece or button 56 is constant when the connections are disconnected or inoperative, and also that said button has another position when the platen sections are connected. It will further be noted that the platen sections or parts have a constant longitudinal relationship which is not varied when the connection or disconnection between them takes place.

The hand controlled line spacing devices which coöperate with the ratchet wheel 31 to turn it and through it the left-hand or main platen and also the tally platen when the clutch devices 64 and 60 are operative, comprise, as shown in Figs. 1, 2 and 5, a pawl 68. Said pawl 68 is pivoted at 69 on an arm 70 which bears rotatably on the sleeve 46. Said arm normally rests against a stop pin 71 which projects from an arm 72 that is variably connectible through a spring plunger 73 with an arm 74 secured to the outer face of the right-hand end plate 10. The plunger 73 terminates in a plunger tooth 75 which is adapted to engage with any one of a series of notches 76 in the arm 74 to provide for variably locating the stop pin 71, the construction thus affording a variation in the normal position of the pawl 68 so that it may coöperate with the line spacing wheel 31 to turn it one or more units of line space distance, the ratchet wheel being controlled between line spacing operations by the usual spring mounted roller detent 77. Actuating devices for the pawl comprise a link 78 by which the pawl is connected with a bell crank 79, said bell crank being connected by a link 80 with a crank arm 81 on a rock shaft 82 which turns in a housing 83 mounted on the carriage truck. Said rock shaft terminates in a downwardly extending handle or finger piece 84 which is operative to actuate said pawl 68 to line space the ratchet wheel 31 and connected parts and also concurrently to restore the carriage from left to right to begin a new line of writing. The pawl 68 and the train of actuating devices therefor down to and

including the handle 84 are common to the No. 11 Remington machine.

Paper feeding devices are provided coöperative with the left-hand or main platen 16 and comprising, as appears from Figs. 8, 9 and 11, feed roller sections 85 constituting a main feed roller and feed roller sections 86 constituting a supplementary feed roller, the main and supplementary feed rollers co-operating with the underside of the platen as is usual. Said feed rollers are mounted respectively on shafts or rods 87 and 88 which are supported on parallel arms 89, said shafts and said arms constituting a rocking frame which is pivotally supported at each side at 90 on three-armed levers 91. The levers 91 bear on a rod 92 which is supported on L-shaped brackets or hangers 93 screwed fast to the frame bar 11. Draw springs 94 connected to the downwardly extending arms of the levers 91 tend to maintain the feed rollers in engagement with the platen 16 and restore said feed rollers to co-operation with said platen after releasing operations. The feed roller sections 85 protrude through slots in a paper apron or deflector 95 of ordinary construction which curves around the under side of and may extend substantially throughout the length of both platens or platen sections (Fig. 1). The devices for releasing the feed rollers comprise fingers or lugs 96 secured to a rock shaft 97 bearing in the ends of the platen frame and operative by a release lever or arm 98 fixed to the left-hand end of said rock shaft. When said arm is pushed rearward from the normal position shown in Figs. 8 and 11 to the Fig. 9 position it rocks the shaft 97 and causes the fingers 96 to co-operate with the upwardly extending arms 95 of the levers 91 to turn said levers on the rod 92, overcoming the springs 94 and throwing off or releasing the feed rollers 85 and 86 as shown in Fig. 9. On releasing the levers 98 the parts will be restored to normal position, the feed rollers and connected devices by the springs 94 and the rock shaft 97 and connected devices by a restoring spring 97 coiled around the left-hand end of said rock shaft and anchored to the platen frame.

The tally strip mechanism proper is mounted as appears from Figs. 1 and 2 on an upright supporting frame of the construction disclosed in my pending applications, Serial Nos. 746,303, filed February 5, 1913 and 762,114, filed April 18, 1913. Said frame comprises upright end plates or arms 99 and 100 and a connecting cross bar 101 enlarged at its ends to receive screws 102 by which the arms or cross bar are secured together, forming a single rigid support or frame. Said support is mounted on the cross rod 12 of the platen frame, said rod passing through the arms 99 and 100. The latter

arm has a hub 103 into which is threaded one or more set screws 104 engaging the rod 12. The supporting frame is arranged near the right-hand end of the rod 12 so that the 5 tally holders mounted on said frame are directly above the tally platen 17. The delivery roll holder or tally supply spool 105 is mounted at the top of the supporting frame on a shaft 106 and in detail construction corresponds with that disclosed in my prior application, Serial No. 762,114, aforesaid. The delivery holder comprises a tube or core 107 and a left-hand flange 108. A 10 socket piece 109 is fixed to the shaft 106 near its right-hand end and receives a friction disk of fiber or the like (not shown) which coöperates with a head 110 of a screw 111 which is secured in fixed relationship with the arm 100 by a check nut 112. At its left-hand end the shaft 106 is coned or pointed as indicated at 113 and engages in a corresponding depression in a bearing pin 114 15 slidable in the arm 99 and provided with a flange 115 and a knurled finger portion 116 between which said pin is engaged by the bifurcated upper end of a leaf spring 117 secured to the arm 99 by a screw 102. Said spring tends constantly to press the pin 114 inward and maintain its engagement with the 20 shaft 106 but the construction permits ready withdrawal of the pin from the shaft so that the latter, together with the tally supply roll may be removed and replaced. When in place the coöperation of the friction disk 25 (not shown) with the socket piece 109 and screw head 110 provides a drag or brake to prevent excess turning movements of the delivery spool. The tally receiving roll holder, spool or carrier 118 is mounted below 30 the delivery holder on the supporting frame and is preferably of the construction disclosed in detail in my prior application, Serial No. 746,303, aforesaid, being mounted and frictionally connected to a shaft 119 35 which bears in the arms 99 and 100. Frictional connections between the holder 118 and shaft 119 are provided comprising a knurled flange 120 rigid with the holder and formed with a depression which coöperates with a circular friction plate or device 40 121 screwed or otherwise secured to the shaft near its left-hand end, a friction spring (not shown) being interposed between the plate 121 and the bottom of the depression in the flange 120. As shown in Fig. 1 the tally strip 123, together with an overlying transfer or carbon strip 124 is wound in roll form 45 on the delivery holder and with the carbon strip is drawn off at the rear side thereof, passing down and around the platen and being connected to the receiving holder winding on the front side thereof. A transverse wire guide or bail 122 supported on the tally frame guides the tally and carbon strips 50 near the receiving spool. The bill sheet or

work sheet which is fed around the left-hand platen 16 may overlie or be superposed on the tally and carbon strips 123 and 124 so that impressions received through the usual inking ribbon on the overlying portion of the bill sheet may be duplicated through the carbon strip 124 on the tally strip 123. Of course, if a short bill sheet is used which does not extend over the tally the carbon strip may be dispensed with and the tally may receive type impressions directly through the ribbon. 70 75

Between the platen and the receiving holder are arranged severing devices of the character disclosed in the pending application of A. W. Smith, Serial No. 742,801 and comprising as illustrated in Fig. 2 a slotted bar 125 and a hand controlled cutting blade 126. The tally and carbon strip pass upward between said bar and said blade so 80 that they may be severed at desired intervals by an actuation of said blade. 85

Means are provided in the present instance for advancing the tally strip independently of the line spacing mechanism 90 which is operative by the handle 84. Said means are illustrated fully in Figs. 1 to 3 and 8 to 10 and comprise generally a pawl and ratchet mechanism which has connections to the tally receiving spool and also to 95 the tally platen. In order to insure the operation of the tally advancing means it has connections with a lock which holds the feed rolls of the platen 16 locked out of operation, said lock being unlocked by the actuation of the tally advancing means. The tally advancing means in this preferred embodiment comprise a hollow tube or shaft 127 which surrounds the rod 12 and bears rotatably on enlargements 128 on said rod. The shaft 127 passes through an opening in the arm 99 and abuts against the arm 100 at its inner face. Suitably fixed to the right-hand end of the shaft 127 is a detent wheel 129 and a pinion 130, said wheel and pinion being suitably fixed together. The pinion 130 meshes with the gear wheel 54 on the right-hand end of the tally platen and meshes also with a pinion 131 secured to the shaft 119 at the right of the tally receiving spool 118. Thus the pinion is connected with both the tally receiving spool and with the tally platen and will transmit motion to them. To retain the pinion 130 and the connected parts in set positions, detent devices coöperative with the detent wheel 129 are provided, said devices comprising a roll 129^a mounted on a spring arm 129^b secured to the cross bar 101. It will be apparent that turning movements communicated to the shaft 127 will be transmitted to the pinion 131, causing the same to turn the roller 118 to wind the tally strip thereon while concurrent movements will be transmitted to the tally platen which will turn 100 105 110 115 120 125 130

in line spacing direction to facilitate the smooth and easy advance of the tally strip. The turning of the tally platen while not strictly necessary to an advance of the tally strip is of service in facilitating such advance, since if the tally platen should remain motionless the tally strip would be dragged over it, thus increasing the power necessary to advance said tally strip and 10 wind it on the receiving spool. The means for turning the shaft 127 to advance the tally as described comprises a ratchet wheel 132 arranged on said shaft near its left-hand end, said ratchet wheel being provided with a hub 133 which fits over the shaft and receives set screws 134 which secure the ratchet wheel in fixed relationship to said shaft. Coöoperative with said ratchet wheel at its underside is an actuating pawl 135, said pawl being provided with a hub portion 136 and a finger piece 137. The hub portion receives a screw pivot 138 which screws into a rocking member or lever 139 and is secured thereto by a check nut 140. Said rocking lever is provided between its ends with a hub portion 141 which fits over and bears rotatably on the rod 12 between the ratchet wheel 132 in the left-hand end bar 10, being confined loosely between said 25 ratchet wheel and end bar. The rocking lever 139, which is coaxial with the shaft 127 and with the ratchet wheel 132, extends fore and aft of the machine transversely of the platen and its forward arm has fixed to 30 it at the end a finger button or key 142. The rear arm of the lever 139 extends or is curved or inclined upward and rearward and its rear face is provided with a cut-out or depression 143 which is adapted for co- 35 operation with a roll 144 rotatable on a headed screw 145 which projects laterally leftward from the release lever 98 above its axis, said depression and said roller co- 40 operating to lock the release lever and the feed rollers 85 and 86 in inoperative position, although normally, as shown in Fig. 8, the locking devices 143 and 144 are separated, the depression or device 143 being 45 above the device or roller 144. The lever 50 139 is maintained in the Fig. 8 position with the under side of its rear arm below the depression 143 in contact with the roll device 144 by spring means comprising in the present instance a draw spring 146 anchored at 55 its forward end to a pin 147 projecting laterally inward from the end bar 10, the opposite end of said spring being hooked over a lateral pin 148 on the rear arm of the lever 139. Thus the roll device 144 in addition to its locking function serves as a stop 60 to determine the normal position of the rocking lever 139.

It will be understood that the provision of the roll 144 minimizes friction and that if desired the roll may be dispensed with

and an ordinary stud or projection employed instead.

To limit the movement of the lever 139 when actuated a stop device is provided, said device being in the form of a pin 149 70 which projects laterally inward from the end bar 10 through a depression or cut-out 150 in the lever 139 below its axis. The pawl 135 is provided with a spring 151 which is coiled around the hub 136 and is 75 secured at its ends in holes formed respectively in the pawl and in the lever 139. Said spring tends constantly to maintain the tooth of the pawl in engagement with the ratchet wheel 132 but may be overcome by 80 pressing down on the finger piece 137 to the rear of the pawl axis. This finger piece 137 is bent horizontally leftward over the top of the lever 139 and is provided at its rear with a downwardly extending lug 137a 85 which is adapted to engage with the top of said lever to limit turning movements of the pawl 135 on its axis 138. These turning movements, it will be understood, will be relative to the lever 139 and are for the purpose of withdrawing the pawl out of operation, when desired.

Referring now to the operation of the pawl and ratchet mechanism it will be understood that when the lever 98 is swung 95 rearward to release the feed rollers 85 and 86 the lever 139 under the action of its spring 146 will automatically turn on its pivotal axis, the under side of the rear arm of said lever 139 riding over the roller 144 100 until the depression or device 143 engages with said roller as shown in Fig. 9. This engagement of the devices 143 and 144 locks the lever 98 in its rear position so that when the operator withdraws pressure from said 105 lever 98 it will not be restored to permit re-engagement of the feed rollers 85 and 86 with the platen but will remain locked off and will hold the feed rollers locked off. During the automatic turning movement of 110 the lever 139 from the Fig. 8 to the Fig. 9 position the tooth of the pawl 135 will slide backward over a tooth of the ratchet wheel 132 to engage with the next preceding notch or space between the ratchet teeth. In ordinary tally strip operations it will be understood that this release of the feed rollers 85 and 86 takes place after the completion of 115 the writing on a bill sheet in order to facilitate the withdrawal of the bill sheet and the insertion of a fresh bill sheet. When a fresh bill sheet has been introduced into the machine over the platen 16 the operator presses the key 142, causing the pawl 135 to coöperate with the ratchet wheel 132 to turn said 120 ratchet wheel and the shaft 127, the movement of the shaft being transmitted as described to the tally spool 118 and to the platen 17. The turning movement of the ratchet wheel and connected parts will con- 125

tinue until the lever 139 is arrested by the engagement of the forward side of the cut-out 150 with the stop pin 149 and the parts are so proportioned and arranged that this extent of movement will properly advance the tally strip so that the next item thereon will be spaced correctly below the preceding item. The actuation of the key 142 also operates to disconnect the cut-out or device 143 from the roller device 144, thus releasing the lever 98 and the feed rollers 85 and 86 and permitting these parts to be restored to normal position by their restoring springs. It will be seen that the function of the lever 139 in locking off the feed rollers affords a check to insure the operation of the tally advancing mechanism since, should the operator overlook such tally advancing operation, his attention will be directed to it by the fact that the feed rollers 85 and 86 are inoperative and that the fresh bill sheet cannot be properly line spaced or advanced from one line to the next by an actuation of the line spacing lever 84. Moreover, these checking or insuring devices come into use automatically at a time immediately following the writing of an item on the tally strip and insure that the tally strip will be line spaced prior to the time when it will be necessary again to write upon it.

Sometimes obviously it will be desirable, as for example when the paper is to be adjusted on the platen 16, to release the feed rollers 85 and 86 and restore them to operation without actuating the pawl and ratchet mechanism 132, 135. Accordingly, when the feed rolls are locked off as in Fig. 9, if it be desired to restore them without actuating the pawl and ratchet mechanism, the operator instead of depressing the key 142 depresses the key or finger piece 137, taking care to press against said finger piece at its rear side and behind the pivotal axis 138. As a result of thus pressing on said finger piece it will be turned on its axis independently of the lever 139 which will remain motionless until the lug 137^a strikes the top of said lever. As a result of this independent turning movement of the pawl 135 its tooth will be drawn out of the ratchet wheel 132, so that if, after the lug 137^a contacts with the top of the lever 139, pressure on the finger piece 137 be continued it will result in the turning of the lever 139 on its axis, releasing the roll device 144 from the control of the device 143 and permitting the feed rollers to return to normal position, the lever 139 turning backward to normal position, carrying with it the pawl 135, the tooth whereof swings clear of the ratchet wheel 132 and does not affect it. This mode of operation will be understood from Fig. 10 which shows the parts just after they have been restored to normal position and before the operator releases the finger piece 137.

Various changes may be made without departing from the spirit and scope of my invention.

What I claim as new and desire to secure by Letters Patent is,

1. In a typewriting machine, the combination of a plurality of platen sections, having a constant longitudinal relationship, disconnectible connections between said platen sections, a push button having a constant normal position when said connections are disconnected, and actuating devices between said push button and said connections. 75

2. In a typewriting machine, the combination of a plurality of platen sections having a constant longitudinal relationship, disconnectible connections between said platen sections, and a push button having a constant normal position when said connections are disconnected and movable axially of said sections to render said connections operative. 80

3. In a typewriting machine, the combination of a divided platen comprising two co-axial sections, disconnectible connections between said sections, a rod provided with a button located at one end of said platen, said rod lying in the axis of said platen, said button when pushed in actuating said rod to cause it to render said connections operative. 90

4. In a typewriting machine, the combination of a divided platen comprising two co-axial sections, disconnectible connections between said sections, a rod provided with a button located at one end of said platen, said rod lying in the axis of said platen, 100 said button when pushed in actuating said rod to cause it to render said connections operative, the pulling out of the button causing said rod to free said connections so that said platen sections are disconnected. 105

5. In a typewriting machine, the combination of a plurality of platen sections having a constant longitudinal relationship, disconnectible connections between said platen sections, and means for controlling said connections including a push button, said button being frictionally retained in set positions during turning movements of said platen sections. 110

6. In a typewriting machine, the combination of a divided platen comprising a plurality of sections, means for at will connecting and disconnecting said sections independently of traveling movements of said platen, line spacing means coöperative with one of said sections, a roll holder for supplying paper to one of said platen sections, means for feeding said paper, and additional paper feeding means coöperative with the other platen section. 115 120

7. In a typewriting machine, the combination of a plurality of platen sections having a constant longitudinal relationship, disconnectible connections between the same, and hand operated devices settable to render said 130

connections effective and ineffective, said hand operated devices being frictionally controlled so that their position remains constant during turning movements of said 5 platen sections.

8. In a typewriting machine, the combination of a plurality of platen sections having a constant longitudinal relationship, disconnectible connections between the same, hand 10 operated devices settable to render said connections effective and ineffective, and pawl and ratchet line spacing devices coöperative with one of said platen sections, said pawl and ratchet devices being effective to line 15 space both platens when said connections are operative, the position of said hand operated devices remaining constant during operations of said line spacing devices.

9. In a typewriting machine, the combination of a divided platen comprising two 20 coaxial platen sections, a line spacing ratchet wheel disconnectibly connected to one of said sections, a hand operated pawl coöperative with said ratchet wheel, devices for 25 connecting and disconnecting said platen sections, a push button at one end of said platen effective to control said devices, and a push button at the oposite end of said platen effective to disconnect said line spacing 30 wheel from the associate platen section.

10. In a typewriting machine, the combination of a plurality of relatively movable platen sections, releasable paper feeding means coöperative with one platen section, 35 only to feed paper over it independently of the other platen section devices for feeding paper over said other platen section, a lock for locking said releasable means in released position, and means for actuating said devices, said last named means being effective 40 to release said lock.

11. In a typewriting machine, the combination of a plurality of relatively movable platen sections, releasable paper feeding 45 means coöperative with one platen section, only to feed paper over it independently of the other platen section, devices for feeding paper over said other platen section, a lock for locking said releasable means in released 50 position, means for actuating said devices, and connections between said last recited means and said lock.

12. In a typewriting machine, the combination of a plurality of platen sections, releasable paper feeding means coöperative 55 with one platen section including a release lever, devices for feeding paper over the other platen section, means for actuating said devices comprising a lever, and means 60 for effecting a locking engagement between the two levers when said release lever is actuated.

13. In a typewriting machine, the combination of a plurality of platen sections, releasable paper feeding means coöperative 65

with one platen section and including a release lever, a locking device on said release lever, paper feeding devices for feeding paper over the other platen section, means for actuating said paper feeding devices including 70 an actuating lever, and a locking device on said actuating lever coöperative with said first recited locking device.

14. In a typewriting machine, the combination of a plurality of platen sections, releasable paper feeding means coöperative 75 with one platen section and including a release lever, a locking projection on said lever, paper feeding devices for feeding paper over the other platen section, means for actuating 80 said paper feeding devices including an actuating lever, and spring means normally maintaining said actuating lever in contact with said projection, said spring means causing automatically a locking engagement 85 between said actuating lever and said projection when said release lever is actuated.

15. In a typewriting machine, the combination of a divided platen comprising two 90 sections, releasable paper feeding means coöperative with one platen section and including a releasing device, a support for a tally strip adapted to be fed over the other section, tally feeding means including an 95 actuating device, a two-part lock for locking said releasing means in released position, one part of said lock being on said actuating device and the other part on said releasing device, and spring means for causing the parts of said lock to coöperate when 100 said releasing device is actuated.

16. In a typewriting machine and in tally strip mechanism, the combination of tally feeding means comprising a ratchet wheel, a 105 lever provided with a finger piece, a pawl, a finger piece for said pawl, and a spring for pressing said pawl into engagement with said ratchet wheel, said lever when actuated through its finger piece causing said pawl 110 to actuate said ratchet, and said pawl when actuated through its finger piece being ineffective on said ratchet wheel but effective to actuate said lever.

17. In a typewriting machine and in tally strip mechanism, the combination of tally feeding means including a ratchet wheel, a lever, a pawl thereon, a stop for said lever, a spring for maintaining said lever against 115 said stop, and means for moving said stop to afford movement of said lever under the actuation of said spring.

18. In a typewriting machine and in tally strip mechanism, the combination of tally feeding means including a ratchet wheel, a 120 spring mounted lever, a spring mounted pawl on said lever, a stop for said lever, and means for moving said stop to afford movement of said lever under the actuation of 125 said spring.

19. In a typewriting machine and in tally strip mechanism, the combination of tally feeding means including a ratchet wheel, a lever coaxial with said wheel, a pawl pivoted on said lever and operative thereby to actuate said ratchet wheel, and means for affording an actuation of said pawl and of said lever through said pawl independently of said ratchet wheel.
20. In a typewriting machine, the combination of a divided platen comprising a plurality of sections; releasable feed roll devices including a release lever, said devices coöperating with one of said sections; tally feeding means coöoperative with the other section, said tally feeding means comprising a ratchet wheel, a pawl, an actuating lever on which said pawl is mounted, spring means operative on said lever, and a spring for pressing said pawl into engagement with said ratchet wheel; and locking devices comprising a projection on said release lever, and a device on said actuating lever engageable with said projection, said spring means causing said locking devices to engage when said release lever is actuated, and said actuating lever being effective to unlock said locking devices.
21. In a typewriting machine, the combination of a divided platen comprising a plurality of sections; releasable feed roll devices including a release lever, said devices coöperating with one of said sections; tally feeding means coöoperative with the other section, said tally feeding means comprising a ratchet wheel, a pawl, an actuating lever on which said pawl is mounted, spring means connected to said lever, and a spring for pressing said pawl into engagement with said ratchet wheel; locking devices comprising a projection on said release lever, and a device on said actuating lever engaging said projection; said spring means causing said locking devices to engage when said release lever is actuated, said actuating lever being effective to unlock said locking devices; and means for affording an operation of said actuating lever and said pawl to release said locking devices without actuating said ratchet wheel.
22. In a typewriting machine, the combination of a tally platen, a tally receiving roll, a shaft, actuating connections between said shaft and both said tally receiving roll and also said platen, a ratchet wheel on said shaft, a pawl for said ratchet wheel, and a lever on which said pawl is mounted, said lever being co-axial with said ratchet wheel.
23. In a typewriting machine, the combination of a tally platen, a tally receiving roll, a shaft, actuating connections between said shaft and both said tally receiving roll and said platen, said actuating connections comprising a pinion on said shaft, a pinion on said tally receiving roll, and a gear wheel on said tally platen, a ratchet wheel on said shaft, a pawl for said ratchet wheel, a lever on which said pawl is mounted, said lever being co-axial with said ratchet wheel, and detent devices for said gear wheel and pinions.
24. In a typewriting machine, the combination of a tally platen, a tally roll supporting frame arranged above said platen, tally delivery and receiving rollers on said frame, a hollow shaft extending through said frame, gear connections between said shaft and both said tally receiving roller and said tally platen, a ratchet wheel on said shaft, a lever coaxial with said ratchet wheel, and a pawl on said lever for said ratchet wheel.
25. In a typewriting machine, the combination of a tally platen, a tally roll supporting frame arranged above said platen, tally delivery and receiving rollers on said frame, a hollow shaft extending through said frame, gear connections between said shaft and both said tally receiving roller and said tally platen, a ratchet wheel on said shaft, a lever coaxial with said ratchet wheel, a pawl on said lever for said ratchet wheel, a platen coaxial with the tally platen, paper feed rollers coöoperative therewith, releasing devices for said feed rollers including a release lever, a projection on said release lever with which the pawl-carrying lever engages, and a spring for maintaining said pawl carrying lever contactive with said projection.
26. In a typewriting machine, the combination of coaxial platen sections, means for delivering a tally strip to one of said sections, feed rollers coöoperative with the other section, releasing means for said feed rollers including a release lever provided with a projection, tally feeding means comprising a ratchet, an actuating lever fulcrumed between its ends, and a pawl on said actuating lever coöoperative with said ratchet wheel, one arm of said actuating lever being provided with a finger piece and the other arm with a device adapted to engage with said projection.
27. In a typewriting machine, the combination of coaxial platen sections, means for delivering a tally strip to one of said sections, feed rollers coöoperative with the other section, releasing means for said feed rollers including a release lever provided with a projection, tally feeding means comprising a ratchet wheel, an actuating lever fulcrumed between its ends, a pawl on said actuating lever coöoperative with said ratchet wheel, one arm of said actuating lever being provided with a finger piece and the other arm with a device adapted to engage with said projection, a spring for maintaining said actuating lever constantly engaged with

said projection, and means for affording an actuation of said pawl and said actuating lever to disengage said device on said actuating lever from said projection but without actuating said ratchet wheel.

Signed at the borough of Brooklyn, city of New York, in the county of Kings, and

State of New York, this 30th day of April, A. D. 1913.

CLIO B. YAW.

Witnesses:

LILLIAN NELSON,
CHARLES E. SMITH.
